UNITED STATES PATENT OFFICE.

ARTHUR O'BRIEN, OF CHICAGO, ILLINOIS, ASSIGNOR TO ARTHUR H. RUGG
AND THOMAS G. McCULLOH, OF CHICAGO, ILLINOIS.

COMBINED PIPE DIE AND REAMER.

SPECIFICATION forming part of Letters Patent No. 746,136, dated December 8, 1903.

Application filed May 19, 1902. Serial No. 107,970. (No model.)

To all whom it may concern:

Be it known that I, ARTHUR O'BRIEN, a citizen of the United States, and a resident of the city of Chicago, in the county of Cook and State of Illinois, have invented certain new and useful Improvements in a Combined Pipe Die and Reamer; and I do hereby declare that the following is a full, clear, and exact description of the same, reference being had to the accompanying drawings, and to the letters of reference marked thereon, which form a part of this specification.

This invention relates to improvements in reamers, and more particularly to a reamer adapted for use in reaming the ends of pipes or tubes during the operation of threading the same.

The invention is an improvement over my prior application for reamers, filed March 24, 1902, Serial No. 99,564.

The object of the invention is to provide a construction at once cheap, simple, and durable and one which admits of providing a relatively long thread on the pipe ends without the removal of the reamer, but which, however, is adapted to permit the reamer to be removed from the die-plate during the threading operation, thereby permitting any desired length of thread to be made upon the pipe.

The invention consists in the matters hereinafter described and more fully pointed out and defined in the appended claims.

In the drawings, Figure 1 is a central vertical section of a device embodying my invention. Fig. 2 is a top plan view of the same. Fig. 3 is a perspective view of the reamer-blade.

A indicates the die-stock, provided with handles α .

B indicates the die, seated in the stock in the usual or any desired manner and held in place by a die-plate C, which, as shown, engages on the top of the die-stock covering the die and provided with a central aperture, through which the pipe end may protrude. Set-screws $c c$ engage the plate to the stock and, if preferred, extend through the ends of the handles α and afford means for attaching the same in the stock. The die-plate, as clearly shown in Figs. 1 and 2, is provided on

diametrically opposite sides of the central aperture with the shoulders C', which are provided with grooves or recesses in the adjacent faces to receive the reamer D. Said reamer, 55 as shown, is a flat blade of steel or other suitable material provided with four sharp cutting edges and having a width approximately equal to the desired diameter of the pipe. Said blade tapers toward a point at its inner 60 or engaging end, as shown in Figs. 1 and 3, and is extended laterally at its upper end and provided with the integral downwardly-directed arms d, which in length approximate the height of the shoulders C' and which are 65 adapted to rest on the die when the reamer is in operative position, thus aiding in centering the reamer in the tube. Set-screws $c' c'$ engage through the shoulders C' and the arms d of the reamer, as shown in Fig. 1, and 70 serve to rigidly bind the reamer in position. The pipe is indicated by X.

The operation is as follows: The reamer when adjusted in position in the die-plate, as shown in Figs. 1 and 2, is of sufficient length 75 for the tapered point thereof to extend into the end of the pipe when the die is in position for threading the same. The tapering of said reamer-blade is such that cutting operation does not commence until the die is well 80 seated upon the pipe or until the first three threads have been formed. As the die passes downwardly over the pipe the blade of the reamer gradually engages the inwardly-turned flange or lip of metal formed when 85 the pipe was cut, and the reaming operation begins and continues until the said lip or flange is entirely cut away and the reamer assumes the position indicated in Fig. 1, with the parallel sides of the reamer engaged with- 90 in the pipe. Should it be desired to produce a long thread upon the pipe, the threading operation may continue until the end of the pipe engages against the top of the reamer. Should it be desired to produce an extra long 95 thread upon the pipe, the reamer-blade may readily be removed by releasing the set-screws c' and withdrawing the blade from the plate, after which any length of thread may be produced. Inasmuch as the width of the 100 blade is approximately equal to the normal bore of the pipe, it is obvious that the reaming

operation will cease when the inturned lip has been removed.

Obviously other means may be used to secure the reamer in position and to permit the removal of the same without removing or loosening the die-plate, and many details of construction may be varied without departing from the principles of this invention.

I claim as my invention—

10 1. The combination with a die-stock, its die and die-plate, of upwardly-extending shoulders on said plate, grooves therein, a reamer slidably secured in said grooves and comprising a flat blade having a tapered point and a plurality of cutting edges.

15 2. The combination with a die-plate having upwardly-directed shoulders on each side of the central aperture, of parallel grooves in the adjacent faces of said shoulders on opposite sides of the aperture and a reamer provided on each side with parallel arms adapted to engage in said grooves and means for securing said reamer in operative position.

20 3. The combination with a pipe-die stock, its die and die-plate, of integral upwardly-extending shoulders on the die-plate on opposite sides of the pipe-aperture, guide-grooves in the adjacent faces of said shoul-

ders and a reamer adapted to be supported partly on the die and rigidly engaged in said shoulders, the point thereof being tapered and extending below the center of the die.

4. As an article of manufacture, a reamer for the purpose specified comprising a plate of metal having parallel sides and sharp angles forming cutting edges and tapering toward a point, and having laterally and downwardly directed arms of equal length on each side of said plate forming a recess between said arms and plate.

40 5. The combination with a pipe-die stock, the die and a die-plate having a pipe-aperture therein, of oppositely-disposed grooved shoulders on said plate, a reamer carried in said grooves, and extending downwardly into the die, and adapted to be inserted or removed from the plate without releasing the plate from the stock.

45 In witness whereof I have hereunto subscribed my name in the presence of two subscribing witnesses.

ARTHUR O'BRIEN.
